CLAIM

The ornamental design for a portable precision guide for powered hand tools, as shown and described.

DESCRIPTION

FIG. 1 is a front elevational view of a portable precision guide for powered hand tools showing my new design;
FIG. 2 is a right side elevational view thereof, the left side being a mirror image thereof;
FIG. 3 is a rear elevational view thereof;
FIG. 4 is a top plan view of FIG. 3.

*Fig. 4**Fig. 3*
